UNITED STATES PATENT OFFICE.

HENRY HOWARD SESSIONS, OF CHICAGO, ILLINOIS, ASSIGNOR TO THE,
PULLMAN'S PALACE CAR COMPANY, OF SAME PLACE.

CAR-PLATFORM BUFFER.

SPECIFICATION forming part of Letters Patent No. 554,007, dated February 4, 1896.

Application filed July 6, 1891. Serial No. 398,470. (No model.)

To all whom it may concern:

Be it known that I, HENRY HOWARD SESSIONS, of Chicago, Illinois, have invented certain new and useful Improvements in Car-Platform Buffers, of which the following is a specification.

My invention relates to car-platform buffers, and has for its object to properly support the buffer-head while permitting it to oscillate freely and vary its position angularly with reference to a vertical plane passing longitudinally through the center of the bar.

In my Patent No. 373,098, dated February 15, 1887, I have shown and described means for connecting the buffer-head with the buffer-rod so as to permit such oscillation, said means comprising an equalizing-bar pivotally mounted upon or connected with the buffer-spring, and two buffer-rods loosely attached at 20 their inner ends to the respective ends of this equalizing-bar, projected forward through suitable guideways in the end platform timber and pivotally connected to the buffer-head on opposite sides of its middle. This construction is efficient when the coupled cars are each provided therewith, but some cars are made with platforms having a central buffer-bar which projects forward and when the cars are coupled transmits the shocks or 25 strains to the middle of the opposing buffer-head. My previous construction, therefore, is not so well adapted for use in trains in which the latter-described construction is employed, because the shock of coupling where 30 the central buffer-stem is employed is often sufficient to fracture the buffer-head, the latter being unsupported at its middle.

The object of my present invention, therefore, is to support the buffer-head at its mid-40 dle while at the same time provision is made for allowing the buffer-head to change its position angularly with reference to a plane passing through the center of the car parallel to its sides.

My invention therefore consists in the combination, with a central buffer-spring carrying an equalizing-bar and two parallel buffer-rods pivotally connected at their front ends to the buffer-head, of a central support pro-45 jected forward by and in line with the spring and preferably with a slight clearance be-

tween its outer end and the rear face of the buffer-head, but adapted when the car is coupled with another having a central buffer-bar to back up or support the buffer-head at 55 its middle.

I am aware that it has been proposed to employ a central buffer-bar pivotally connected at its front end to a buffer-head in combination with side buffer-bars also pivotally connected at their front ends to the buffer-head and at their rear ends to an equalizing-bar. This construction I avoid, because the connection of the three rods or bars at separated 60 points with the buffer-head greatly restricts 65 the capacity of the buffer-head to oscillate or change its angular position with reference to the axis of movement of the buffer-head and bars.

In the accompanying drawings, Figure 1 is 70 a plan view of the end of one car and a sectional plan view of the end of an adjoining car coupled thereto, the buffer connection being shown in dotted lines. Fig. 2 is a similar view of a central portion of the platforms, 75 broken away to show the buffer connection; and Fig. 3 is a side elevation, partly broken away.

In the drawings, 5 represents the platform and 6 the end timber thereof. 80

7 is a buffer-spring which is positioned centrally of the car and carries thereon the equalizing-bar 8, in the ends of which are mounted the buffer-rods 9, which project forward through guides 10 in the end platform timber 85 and are pivotally connected at their forward ends to the buffer-head 11, the pivots being marked 12.

13 represents a central supporting-bar which is seated against spring 7. This supporting-bar 13 is constructed in two parts, the rear member being yoke-shaped and the forward member has a stem projected through a longitudinal aperture in the yoke and having a key 14. Bar 13 projects forward in line 95 with the spring 7, its forward end being preferably rounded, as seen in Figs. 1 and 2, and in its normal position falling short of the buffer-head, so as to permit a slight clearance, as shown in the drawings. 100

15, Fig. 2, represents a central buffer-bar such as is employed in one style of platform

now in common use. This figure shows a car provided with my improved construction coupled to one of said common construction having the central buffer-bar, and this buffer-bar, as is seen, impinges upon the middle of the buffer-head, and the latter, if unsupported, might be broken by the shock of coupling. But with the central support therefor flexure of the buffer-bar only would be permitted, whereupon it could come in contact with said support and be reinforced or backed up thereby. The round end of this central supporting-bar permits the buffer-head to change its angular position with reference to the spring freely and unobstructedly, which would not be the case if the central support were pivotally connected to the buffer-head.

I claim—

In a car-platform buffer the combination with an outwardly-forcing buffer-spring coil, 20 of an equalizing - bar carrying buffer - rods adapted to slide through ways in the platform, a buffer-head pivotally connected to said buffer-rods and a central support for the buffer-head comprising a bar constructed in two 25 parts, one having a pivotal bearing upon the buffer-spring coil and the other member having a rounded head and a stem passing through a longitudinal aperture in the rear member, substantially as described.

HENRY HOWARD SESSIONS.
